United States Patent Office

Des. 180,987
Patented Sept. 17, 1957

180,987

COUNTER DISPLAY CASES

Samuel Ayres, Jr., Marblehead, and Wallace A. Underwood, Sherborn, Mass., assignors to The Gillette Company, Boston, Mass., a corporation of Delaware

Application September 23, 1955, Serial No. 38,070

Term of patent 14 years

(Cl. D80—11)

Fig. 1

Fig. 2

Fig. 1 is a perspective view of a counter display case showing our new design, and

Fig. 2 is a front elevation thereof.

The characteristic feature of our design for the counter display case disclosed resides in the front and two side walls having the configuration shown.

The rear portion of the case is substantially plain.
We claim:

The ornamental design for a counter display case, as shown and described.
